UNITED STATES PATENT OFFICE.

FRANKLIN L. BAILEY, OF BOSTON, MASSACHUSETTS.

ENGRAVER'S RULING-MACHINE.

SPECIFICATION forming part of Letters Patent No. 363,942, dated May 31, 1887.

Application filed October 25, 1886. Serial No. 217,179. (No model.)

To all whom it may concern:

Be it known that I, FRANKLIN L. BAILEY, a citizen of the United States, residing at Boston, in the county of Suffolk and State of Massachusetts, have invented new and useful Improvements in Engravers' Ruling-Machines, of which the following is a specification.

The first part of my invention is found in that part of engravers' ruling-machines known as the "pawl attachment," which turns the ratchet-wheel and the main screw. It consists of limiting the movement of the pawl on its hinge sufficiently to just clear the teeth of the wheel in the reverse movement of the pawl-handle, the pawl being pressed out of engagement with the teeth by the finger against a stop. The importance of lifting the pawl from the teeth comes from the liability of turning the screw backward, the wearing of the teeth, and noise resulting when the pawl drags over the teeth in this reverse movement. In feeding, the finger, with its varying and uncertain strength, feeling the impact against this stop, continues it by pressure, while the hand and wrist go through the reverse movement of the handle with comfort and greater exactness, though the handle constantly takes different angles with regard to them.

The second part of my invention consists in an arrangement for the automatic dropping onto and raising of the cutter from the block, so that the hand feeding the screw may remain at the feed-handle and not pass to the cutter for every line cut, these parts not being at all in the operator's way or light. Greater speed in working resulting, and, because the cutter-holder is not touched by the hand and is free from its irregularities of weight and strength, there is much more evenness and delicacy in the work produced; but this automatic apparatus is applicable only to a portion of the work required. On account of a constant variation of the lines required as to depth in some kinds of work, the usual method of depression of the cutter by hand cannot be dispensed with with economy. So, by proper adjustment of parts I am able to suspend the automatic action and take up that of hand-work, and in this alternation, effected with great facility, is found an important part of my invention. This mechanism is fully illustrated in the accompanying drawings, in which—

Figure 1 is a top view of the entire machine. Fig. 2 is a side elevation with the beam and carriage-slide cut away on lines x x' , Figs. 1 and 2, showing the cutter in its position when lifted from the block, and the position of mechanism corresponding automatically used. Fig. 3 is an end view corresponding with Figs. 1 and 2, showing the pawl in its intermediate position; also, the position of the automatic apparatus, but the cutter resting on the block; also, showing the position of the wave-ruled cylinder. Fig. 4 is a magnified side view of as much of this machine as will show these machines as now used, the automatic parts being suspended from operation. Figs. 5 and 6 are magnified detached views of the ratchet-wheel pawl, its handle, and spring, showing the position of the button-stop and related parts.

The same letters refer to similar parts in the several drawings.

A is the frame of the machine, which supports all the moving parts, this frame having two extensions out from its opposite sides upon which are planted posts which support the two ends of a beam, B, upon which beam, moving on ways, is a slide or carriage, C, which slides with all upon it toward and from the operator. D is a fixed bracket on this slide, which carries pivoted at its top and bottom ends a frame, E, which in turn has hinged at its outer and inner ends the vibrating tool-holder H, which also has upon it, at its front and free end, the cutter h, its regulating-screw I, and foot or shoe I', the screw and shoe regulating the depth and width of the lines cut. The free end of the holder H is moved upward from the block by the flat spring K, being pressed downward by the hand. (Seen in Fig. 4.)

Upon the front end and top of the frame E is a tracer, L, of the surface of the figured cylinder M, the point of this tracer being pressed against the cylinder by the spring e e, Figs. 1 and 3, behind the lower part of the frame E. When that class of work is not required, E is held fixed by a set-screw behind in bracket D.

Upon the frame of the machine A A, upon ways at A' A', moving at right angles to the carriage-slide and motion of the cutter, is the table T and T', whose upper surface, carrying the engraved block N, is so placed that the

block can be met by the point of the cutter *h*. This table *T* is moved right and left by the main screw *S*, moving on supports at its ends *S* *S*². (Seen in Figs. 1 and 2.) Upon the end 5 of *S*, at the extreme left, is fixed a ratchet-wheel, *W*, Figs. 1, 2, and 3. The support *S*² of the screw is also that of the disk *U*, through the center of which extends the screw-bearing. Upon this disk, between it and the ratchet-wheel, on a neck swings the feed-handle *V*, whose upward swing is regulated by the movable gage *V'*, placed on the outer edge of the disk. The pawl-handle *V* carries pivoted on a stud the pawls *Z* *Z* and their cam *Y*, which 5 together are swung on their stud by the pressure of the point of the spring *Y'* upon the inclined surfaces of the cam *Y*; also, a button or stop, *J*, which stops or stays the movement of the pawl after its points are disengaged from 10 the teeth in ratchet-wheel *W*. The relative situation of these parts is seen in Fig. 3, where the pawl is seen not operating, the spring being at a dead-point notch.

Figs. 5 and 6 represent the upper point of 5 the pawl as feeding. That the pawl points may not drag over the teeth upon the reverse movement of the handle, it is pressed out of engagement by the finger against the stop *J*, which in this case is in position over the cam *Y*; but when feeding in the opposite direction, and the lower point engages the teeth, the point of the stop *J* enters the square cavity in the cam, so that the finger pressing upon the upper half of the pawl the lower point is disengaged, this stop arresting the movement of the pawl at a point well free from the teeth. As the pressure of the fingers is irregular and uncertain, and that the dead-point may be avoided, and because the pawl 5 handle assumes different angles with the hand and arm, I make use of this stop to give composure to the fingers operating. If it be a single-pointed pawl, and that one a hook hooking onto the teeth made at a proper angle, I think it would be the same as this in principle if a stop were used to stay its movements.

That the hand which does the feeding may remain at the pawl-handle continuously, I have provided means for dropping the cutter 5 and raising it by the swing-lever *F*, hinged close to the pawl-handle so that the thumb and fingers can clasp it while still encircling the pawl-handle, and swing, after the feed is made, into the position shown in dotted lines as that of the pivot of the rod *R*, Fig. 1, which rod connects at its other end with the lower end of the stem *P*², extending down from a lifting-plate, *P*, pivoted at opposite sides of the frame in the upright posts, this plate lying underneath the bed *B* and parallel with the course of the cutter. By a counter-balance, *P'*, the plate is raised in its movement upward into a level position, sidewise considered. This weight is sufficient also to raise the free end of the toolholder *H* and its cutter by means of an arm, *G*, extending from the inner side of the toolholder to the edge of the plate and resting

upon it. As the carriage *C* moves back and forth, the tool-holder will be held up over the whole extent of the engraved block; but when 70 the plate is swung downward the holder and cutter will follow until the latter will rest upon the block. The cutter-holder is drawn downward by a flat spring, *K*², extending from the under side of the bracket *D*, the spring taking hold of a hook on arm *G*. The hand at *F* bears the plate down until the cutter rests on the block, and still a little farther against a stop, so that *G* will be free from contact with the plate when the lines are cut. It will be 80 seen also that the lateral movement of the toolholder and its frame *E* and the cutter, caused by the tracer *L* following the surface of the wave-rule, will not in the least be disturbed.

I have said above that the spring *K*, which is 85 alongside of *K*², serves to lift *H*. When the just-described automatic dropper is used, the spring *K* is swung from under *H* and is inoperative, and *K*² is put into use on its hook. When the automatic apparatus is no longer 90 desired, the spring *K*² is removed from its hook, the spring *K* is replaced under *H*, and the plate *P* is fastened in its lowest position by means of the latch *Q*, hinged to the inside of one of the posts of the frame, taking hold on a pin on stem 95 *P*², as clearly shown in Fig. 4, which shows the relative position of all the parts when the cutter is pressed into service by the hand on *H*.

What I claim as my invention, and desire to secure by Letters Patent, is—

1. In an engraver's ruling-machine, the combination of a work-carrying carriage, a feed-screw for moving said carriage, a ratchet-wheel secured upon said screw, a lever mounted upon and movable about the axis of said screw, a pawl carried by said lever and constructed and arranged to engage with the teeth of said ratchet-wheel, and to be retracted therefrom by the hand of the operator, a stop constructed and arranged to limit the movement of said pawl when retracted, and a spring arranged to press said pawl into engagement with said ratchet-wheel.

2. In an engraver's ruling-machine, the combination, with a work-supporting carriage, a feed-screw for moving said carriage, a ratchet-wheel secured upon said screw, and a hand-lever mounted upon and movable about the axis of said screw, of a pawl pivoted upon said hand-lever in position to engage with the teeth of said ratchet-wheel, a cam firmly fixed to said pawl, so as to be movable therewith, and provided with a peripheral cam-surface and a dead-point, a spring constructed and arranged to press alternately upon said cam-surface and dead-point to hold said pawl in engagement with the ratchet-wheel or out of engagement therewith, and a stop to limit the movement of the pawl about its axis when retracted from engagement with said ratchet-wheel.

3. The combination of the lever *V*, the cam *Y*, the spring *Y'*, the movable stop *J*, and the pawl *Z*, all constructed, arranged, and oper-

ating substantially as and for the purposes described.

4. As a means of alternately or interchangeably depressing the tool-holder to bring the cutter into action upon the work automatically or by hand, the combination, with a pivoted tool-holder, of two springs constructed and arranged to be interchangeably connected to said tool-holder, one to press said holder upward and the other to press it downward, a lifter-bar for raising the tool-holder against the tension of the downwardly-pressing spring, and a stop for locking said lifting-bar in its retracted position.

15 5. The combination of the tool-holder H, provided with the arm or lug G, a spring for pressing said holder downward, a lifter-bar for raising said tool-holder, and mechanism, substantially as described, for moving said lifter-bar through a greater arc of descent than the fall of said arm G; whereby said bar will be removed from all contact with said arm while the line is being cut.

6. The combination, with a pivoted tool-holder and a spring for pressing said holder downward into contact with the block to be cut, of the rocker-lifting plate P, the arm G, projecting from the tool-holder above the free edge of said plate, the counter-balance P', secured to said lifter-plate upon the side opposite to the arm G, the lever F, the rod R, and lever P², all constructed, arranged, and adapted to operate substantially as described.

7. The combination of a pivoted tool-holder provided with a laterally-projecting arm or lug, a lifter-bar arranged to engage with the under side of said arm or lug to raise said

tool-holder, and means, substantially as described, to retract said lifting-bar and permit the automatic descent of said holder.

8. In an engraver's ruling-machine provided with a pivoted tool-holder constructed and arranged to be vibrated vertically and horizontally, a wave-line shaft or bar, and a tracer arranged to bear against said wave-line 40 bar, and a lifter-bar for raising said tool-holder, in combination with means, substantially as set forth, for raising and depressing said lifting-bar, and an arm or lug projecting from said tool-holder over said lifter-bar a sufficient 45 distance to be struck by said bar when moved upward whether the tool-holder be at one extreme or the other of its lateral vibration.

9. In combination with a pivoted tool-holder provided with a laterally-projecting 50 arm or lug, a lifter-bar for raising said tool-holder, mechanism, as set forth, for moving said lifter-bar through a distance greater than the descent of said lug or arm, and a stop for locking said lifter-bar at the extreme of its 55 downward movement and out of the path of said arm or lug when the tool-holder is being depressed by hand.

10. The combination of the holder H, a lifter-bar for raising said holder, and mechanism, substantially as set forth, for operating said lifter-bar, said bar being located beneath or behind the beam B, so as to be removed 60 from the operator's view of the work while the lines are being cut.

FRANKLIN L. BAILEY.
